UNITED STATES PATENT OFFICE

WALTER RUSILAS, OF PATERSON, NEW JERSEY

DESIGN FOR A PIN AND NEEDLE STAND

Application filed October 15, 1930. Serial No. 37,261. Term of patent 7 years.

To all whom it may concern:

Be it known that I, WALTER RUSILAS, a citizen of Lithuania, residing at Paterson, in the county of Passaic and State of New Jersey, have invented a new, original, and ornamental Design for a Pin and Needle Stand, of which the following is a specification, reference being had to the accompanying drawings, forming part thereof.

Figure 1 is a perspective view of a pin and needle stand, showing my new design,

Figure 2 is a top plan view thereof, and

Figure 3 is an end elevational view thereof.

I claim:

The ornamental design for a pin and needle stand, as shown.

WALTER RUSILAS.
